UNITED STATES PATENT OFFICE.

LEONARD B. TERHUNE, OF NEWARK, NEW JERSEY, ASSIGNOR TO E. I. DU PONT DE NEMOURS & COMPANY, OF WILMINGTON, DELAWARE, A CORPORATION OF DELAWARE.

SEPARATING MACHINE.

1,409,500.

Specification of Letters Patent. Patented Mar. 14, 1922.

Application filed April 29, 1918. Serial No. 231,499.

To all whom it may concern:

Be it known that I, LEONARD B. TERHUNE, of Newark, in the county of Essex and in the State of New Jersey, have invented a certain new and useful Improvement in Separating Machines, and do hereby declare that the following is a full, clear, and exact description thereof.

My invention comprises a machine for applying force to a member or to members held together, in such a way as to pull apart said member or members into separate pieces.

The object of my invention is to provide a machine of the above character which may be used for readily separating the individual combs in pairs of combs commonly known as "twin combs", and which are provided with interlocking teeth made by cutting with knives. In the cutting process combs are made in pairs, as for example from a rectangular sheet or block of celluloid and by cutting through the sheet or block by means of knives to form the teeth of two combs having the teeth of the respective combs facing each other and interlocking with one another. When combs are made in this manner it has been found difficult to separate the two combs from each other as the separation has been ordinarily effected by hand. Because of the difficulty of separating the combs, however, a considerable amount of time has been consumed in this step of the process, and some of the combs were so tightly fastened together that they could not be separated by hand. It is the object of my invention to provide a machine which may be used to carry out this step of the process which machine will operate quickly and easily to separate the combs and without deforming them. However it will be understood that the machine is not limited to use for separating combs. Further objects of my invention will appear from the detailed description thereof contained hereinafter.

While my invention is capable of embodiment in many different forms, for the purpose of illustration, I have shown only one form thereof in the accompanying drawings, in which

Figure 1 is a front elevation of a machine made in accordance with my invention, certain parts appearing in section;

Figure 2 is a side elevation of the same;

Figure 3 is a plan view of the upper portion of the same; and

Figure 4 is an enlarged diagrammatic plan view, showing the combs in different positions.

In the drawings I have shown a pair of wooden supporting blocks 1 and 2 which support a pair of uprights 3 and 4 attached together at their upper ends by means of a bed plate 5. The upright 3 is provided near its lower end with journaled bearings 6 to receive a shaft 7, on which a hand lever 8, having a handle 9, is pivotally carried, said shaft 7 furthermore being provided with a lever arm 10 which is normally moved upwardly by means of a spring 11 attached at one end to said lever 10, and at the other end to the upright 4. The extreme end of the lever 10 normally rests against a stop 12 which forms a cross bar 75 passing across the lower portion of the upright 4. At its central portion the lever 10 is connected by a link 13 to a bell crank lever 14 carried upon a pivot 15 in a pair of brackets 16 extending downwardly from the bed plate 5. Said plate 5 has extending longitudinally through the same, a dovetail groove 17 to receive three slides 18, 19 and 20. The slide 20 has an opening 21 therein to receive the upper end of the bell crank lever 14, a slot 22 being provided in the plate 5 to permit the bell crank lever 14 to pass through the same. On said slide 20 there is provided a plate 23 secured thereto by screws 24, said plate having in the upper surface thereof two cam grooves 25 and 26 located at an acute angle to each other, and which are provided to receive respectively a pair of rollers 27 and 28. The rollers 27 and 28 are carried upon the ends respectively of levers 31 and 32, which are provided respectively with jaws 33 and 34 to engage a pair of combs 35 and 36. The levers 31 and 32 are pivotally connected by means of arms 37 and 38 to a single pivot 39 carried upon the slide 18, and which is held in its adjusted position by means of a set screw 40 in the plate 5. Upon the central slide 19 there is located an abutment 41 to support the rear ends 100 of the combs 35 and 36, a set screw 42 being provided to hold said slide 19 in its adjusted position.

In the operation of my invention, a pair of "twin combs" are inserted between the 110

arms 37 and 38 in such a manner that their rear ends rest against abutment 41, and in such a way that the jaws 33 and 34 engage the two combs outside of the position of the 5 teeth thereon. If necessary, the positions of the slides 18 and 19 may be adjusted so that the particular pair of combs will be properly positioned in this manner. Thereupon the hand lever 8 is operated, which brings about 10 the rearward movement of the slide 20, thus causing the jaws 33 and 34 to firmly grasp the respective combs, and at the same time pull them apart. It will be observed from an inspection of the assembled parts as 15 shown in the drawings (particularly Fig. 3), that the short levers 31 and 32 bearing the jaws 33 and 34 may have a pivotal movement upon the long arms 37 and 38 independent of any movement of these arms; also that 20 the short levers 31 and 32 may have a movement together with the arms 37 and 38, the latter swinging upon the pivot pin 39. When the unseparated parts of the comb are inserted between the long arms 37 and 25 38, as shown in Fig. 4, and the cam-plate 23 is moved inwardly, the first-mentioned movement is that which necessarily first occurs,—that is, the cam-grooves 25 and 26 spread the rollers 27 and 28 apart, thus 30 pivoting the short levers 31 and 32 upon the arms 37 and 38, this movement carrying the jaws 33 and 34 in an arc inwardly toward and at an angle to engage with the end surface of the comb, thus causing these jaws to 35 firmly grip and, in fact, to bite into the end surface of the comb, as shown in Fig. 4, a biting tooth being provided upon each jaw, as shown in Figs. 3 and 4. A continued movement of the cam-plate produces a 40 further separation of the rollers 27 and 28, and since during this movement the jaws 33 and 34 are in engagement with the end surface of the cone, the spreading of the rollers 27 and 28 produces a spreading of 45 the jaws 33 and 34 bodily with a spreading movement of the arms 37 and 38 about the pivot 39, the spreading movement of the jaws separating the two portions of the comb, as shown in Fig. 4. Throughout the entire 50 separating movement, however, it will be noted that the jaws 33 and 34 will maintain their positions parallel to the ends of the twin combs. In this way the twin combs will be readily separated and with a minimum 55 amount of effort, and by this means combs may be separated which could not possibly be separated merely by hand.

While I have described my invention above in detail, I wish it to be understood that 60 many changes may be made therein without departing from the spirit of the invention.

I claim:

1. A separating machine having an abutment adapted to engage one surface of the 65 work to be separated, a pair of pivoted arms

having their free ends adjacent the opposite surface of the work, levers pivoted respectively to said arms, jaws carried by said levers adapted to engage the last mentioned surface of the work, and a cam member 70 movable with regard to said levers having cam surfaces cooperating therewith to spread said jaws to separate the work.

2. A separating machine comprising jaws adapted to engage the work on opposite 75 sides of the line at which the work is to be separated, pivoted levers respectively carrying said jaws, and means for moving said levers in one direction to force said jaws into engagement with the work and spread 80 the jaws to separate the work.

3. A separating machine comprising a pair of movable arms, levers connected respectively to said arms and carrying jaws adapted to engage the work on opposite 85 sides of the line at which the work is to be separated, and means independent of said arms for moving said levers to separate said jaws.

4. A separating machine comprising a 90 pair of arms pivoted at a point substantially in line with the longitudinal axis of the work to be separated, levers pivoted respectively to said arms and each carrying a jaw adapted to engage the work on opposite 95 sides of the line at which the work is to be separated, and a movable plate having cam surfaces engaging with said levers to separate said jaws when said plate is moved.

5. A separating machine having an abutment to engage one surface of the work to be separated, said abutment adapted to form a pivot for the separating portions of the work, and jaws operating upon a surface of said work opposite said pivot to separate 105 said work progressively and completely to said abutment.

6. A separating machine having a pin abutment adapted to engage one surface of the work to be separated and in the line 110 of separation, jaws adapted to engage an opposite surface of the work to be separated and respectively on opposite sides of the line of separation, and means for spreading said jaws to separate the work.

7. A separating machine having an abutment to engage one surface of the work to be separated, said abutment adapted to form a pivot for the separating portions of the work, pivoted arms adapted to respectively 120 engage surfaces of said work upon opposite sides of the line at which the work is to be separated, jaws carried by said arms adapted to receive surfaces of the work respectively on opposite sides of said line of separation, 125 and means for spreading said jaws to separate said work.

8. A separating machine having an abutment adapted to engage one surface of the work to be separated, jaws adapted to en- 130

- gage another surface of the work respectively on opposite sides of the line at which the work is to be separated, means for spreading said jaws to separate said work, and
- 5 means independent of said first-mentioned means to relatively adjust said abutment and jaws to vary the distance between said abutment and said jaws.
9. In a separating machine having a portion for bodily supporting the work to be separated, pivoted arms adapted to respectively engage surfaces of said work upon opposite sides of the line at which the work is to be separated in all positions of separation
- 10 of said work, jaws carried by said arms adapted to engage surfaces of the work respectively on opposite sides of said line of separation, and means for spreading said jaws to separate said work.
- 15 10. A separating machine having an abutment adapted to engage one surface of the work to be separated, jaws adapted to engage another surface of the work respectively on opposite sides of the line at which the
- 20 work is to be separated, means for moving said jaws at an angle to the said surface to be engaged into said engagement, and for thereafter spreading said jaws in a line substantially parallel with said engaged surface
- 25 to separate said work.
11. A separating machine having an abutment adapted to engage one surface of the work to be separated, pivoted jaws adapted to engage another surface of the work re-
- 30 spectively on opposite sides of the line at which the work is to be separated, means for
- 35

moving said jaws upon said pivots into engagement with said work, and for thereafter spreading said jaws and said pivots to separate said work.

12. A separating machine having an abutment adapted to engage one surface of the work to be separated, jaws each having a tooth adapted to engage another surface of the work respectively on opposite sides of the line at which the work is to be separated, means for forcing said jaws into biting engagement of said teeth with said surface to be engaged, and for thereafter spreading said jaws to separate the work.

13. A separating machine having an abutment adapted to engage one surface of the work to be separated, a pair of levers, jaws pivoted to said levers and adapted to engage another surface of the work respectively on opposite sides of the line at which the work is to be separated, means for moving the jaws upon said levers into engagement with said work and for thereafter moving said levers to separate said jaws.

14. A separating machine having an abutment to engage one surface of the work to be separated, separating jaws mounted upon an opposite side of said work from said abutment, means for moving said jaws toward said abutment into engagement with said work, and means for thereafter moving said jaws apart in a line substantially parallel with said abutment.

In testimony that I claim the foregoing I have hereunto set my hand.

LEONARD B. TERHUNE.
